UNITED STATES PATENT OFFICE

JOHN R. L. SANTOS, OF BALTIMORE, MARYLAND, ASSIGNOR TO THE BARTLETT HAYWARD COMPANY, OF BALTIMORE, MARYLAND, A CORPORATION OF MARYLAND

GAS HOLDER

Application filed August 29, 1928. Serial No. 302,782.

This invention relates to gas holders and particularly to gas holders of the waterless type.

A waterless gas holder ordinarily comprises a vertical shell of cylindrical or prismatic form and a piston movable vertically in the shell to vary the effective volume within the shell, that is, the space beneath the piston. It is important that the piston be sealed gas tight to the shell and that this seal impose no great resistance to the movement of the piston.

In a copending application Serial No. 302,781 filed August 29, 1928, I have described a packing structure consisting of an annulus built up of fabric laminæ and having a flanged or angular section. One flange of the packing member lies against the periphery of the piston and the other extends radially outward into edge contact with the shell. The present application is subordinate to said copending application and is directed to a particular arrangement of the structure claimed herein in which lubricant is fed through the body of the packing structure by pressure exerted on the lubricant by gas in the holder. Consequently, the claims of the present application are not drawn broadly to the laminated packing structure disclosed, 30 that subject matter being reserved for the copending application.

The preferred embodiment of the present invention is illustrated in the accompanying drawing, in which:

Fig. 1 is a fragmentary plan view partly in section;

Fig. 2 is a fragmentary vertical section; and

Fig. 3 is a fragmentary perspective view 40 of the packing element.

A portion of the shell of the gas holder, here indicated as cylindrical, is shown at 6. The piston comprises a top plate structure 7 and a depending peripheral skirt or flange 8.

The skirt 8 is materially smaller in diameter than the shell 6 and in the interval between them at the lower margin of the skirt 8, is an annular trough made up of the channel

member 9 and an annular plate 11. This is 50 intended to retain a bath 12 of lubricant such

as tar, oil, or other suitable mobile material. The trough completely encircles the piston. Mounted with one flange submerged in the lubricant bath 12 is a packing structure indicated generally by the numeral 13 and conforming generally to the disclosure of my copending application above identified. That is to say, it is made up of layers 14 of felt and 15 of canvas, alternating with each other, certain of the felt layers being interrupted as indicated at 16 to provide oil ports which extend from the lubricant bath 12 through the packing to the contact area between the packing and the shell 6.

As clearly illustrated in the drawing the packing is of angular or flanged cross section. One flange rests in face engagement with the skirt 8 and is clamped between this skirt and an annulus 17 by the bolts 18, of which only one is shown. From its point of attachment to the skirt 8 the packing extends upward and outward into edge contact with the shell 6. Adjacent the contacting edge it is provided with a series of clips 19. These are attached by bolts 21 which serve the further purpose of clamping together the laminæ which make up the packing structure 13. Each clip 19 is pivoted to a lever 22 which is hinged at 23 on a corresponding bracket 24. The bracket 24 is riveted to the plate 7. Each lever 22 carries a loading weight 25 which is for the purpose of causing the lever 22 to urge the packing structure 17 into sealing contact with the shell 6.

Obviously the pressure of gas beneath the piston structure exceeds the atmospheric pressure above the piston for the gas is supporting the entire weight of the piston. It follows, therefore, that the gas pressure acting on the upper surface of the lubricant bath 12 forces lubricant through the ports 16 to the contact area between the packing structure 13 and the shell 6. The trap 26 is provided merely to prevent leakage of gas through the condensate drain port 27. This port drains any liquid which condenses above the packing ring 13 and discharges it into the holder.

The piston is centered and guided by rollers 28 which are carried by brackets 29.

on the piston and engage the interior face of the shell, only one bracket and roller being shown.

The invention may be embodied in various alternative forms within the scope of the appended claims.

What is claimed is:

1. In a waterless gas holder the combination of a shell; a piston movable in said shell to vary the effective volume thereof; a seal for said piston comprising a fabric structure surrounding and carried by the piston, said fabric structure being formed with lubricant ports; means located beneath the seal for retaining a bath of lubricant subject solely to the pressure of the gas obtaining within the holder and into which bath the fabric extends; and yielding means for urging said sealing structure into sealing engagement with the shell.

2. In a waterless gas holder, the combination of a shell; a piston movable in said shell to vary the effective volume thereof; a seal for said piston comprising a laminated fabric structure surrounding and carried by the piston, said fabric structure being L-shaped in cross section and curved outward from said piston into edge contact with the shell, said fabric structure being formed with lubricant passages extending in the direction of the laminæ; a lubricant reservoir in communication with said passages, said reservoir being located below the seal and subject solely to the gas pressure obtaining within the holder; and yielding means for urging said structure into sealing engagement with the shell.

3. In a waterless gas holder, the combination of a shell; a piston movable in the shell to vary the effective volume thereof; a laminated annular seal of substantially L-shape in cross section, one flange extending to edge contact with the shell and the other surrounding the piston and directed downward; and means for feeding lubricant through said seal in the general direction of the laminæ comprising a lubricant bath into which said downwardly extending flange extends, said lubricant bath being located beneath the seal and subject solely to gas pressure obtaining within the holder.

4. In a waterless gas holder, the combination of a shell; a piston movable in the shell to vary the effective volume thereof; a packing seal on the piston and engaging the shell; means for retaining a lubricant bath below the area of engagement of said seal with the shell and subject solely to gas pressure obtaining within the holder; and connections for delivering to said area lubricant urged by such gas pressure.

5. In a waterless gas holder, the combination of a shell; a piston movable in the shell to vary the effective volume thereof; a packing element contacting the shell; means for retaining a lubricant bath into which a por-

tion of the packing element dips, said bath being subject solely to the pressure obtaining within the holder; and means to deliver lubricant from the bath to the area of contact of the packing element with the shell under gas holder pressure.

6. In a waterless gas holder, the combination of a shell; a piston movable in said shell to vary the effective volume thereof; a seal for said piston surrounding and carried by the same, said seal being formed of absorptive material; means located beneath the seal for retaining a lubricant bath into which bath the seal extends, said bath being subject solely to the pressure of the gas obtaining within the holder and into which bath the seal extends; and means for urging said sealing structure into contact with the inner wall of the shell.

7. A waterless gas holder as set forth in claim 6, wherein a trap is mounted within the piston and has its upper end opening outwardly through a drain port located above the seal.

In testimony whereof I have signed my name to this specification.
